DISPENSING CAP FOR COLLAPSIBLE TUBES,
HAVING SPRING-BIASED OUTLET ELEMENT
ACTUATED BY PRESSURE OF TUBE
CONTENTS

Lawrence J. Gardiner, Bridgeport, Conn.

Application November 27, 1946, Serial No. 712,668

1 Claim. (Cl. 222—496)

1

The present invention relates to an automatic dispensing cap for paste tubes and the like, and has for an object to provide a cap of this character which may be readily attached to a standard type of tube upon removal of the regular cap, or which, if desired, may be provided as an original part of the tube by the manufacturer.

A further object is to provide a cap which may be conveniently and economically constructed from moulded plastic material, and wherein the movable parts will maintain an accurate fit and operative relation over a long period of use.

Another object is to provide a cap having a spring pressed valve closure member adapted in its closed position to close both the regular outlet opening of the tube and the outlet slot of the cap, and which is adapted to be moved to open position through pressure of the material contained in the tube upon pressing the sides of the tube. It is particularly proposed to provide a cap having an outlet slot provided with relatively sharp edges along its upper and lower sides, and in which the surfaces of the cap extending outwardly from the upper and lower edges of the slot are widely divergent, and to further provide the valve member cooperating with the outlet slot with a relatively-sharp-edge which is adapted in its closing movement to have a shearing action in cooperation with the edges of the slot. Thus, the possibility of a small amount of the extruded material remaining in the slot is prevented. This has been an objectionable feature of automatic caps heretofore in use, wherein a small amount of material would remain in the orifice, becoming hardened and impairing the proper operation of the automatic cap.

Another object is to provide a cap having an outlet slot provided along its lower edge with tooth portions, which impart to the extruded material a series of grooves along its under side so that the extruded material will not tend to slip off a brush or the like.

With the above and other objects in view, an embodiment of the invention is shown in the accompanying drawings, and this embodiment will be hereinafter more fully described with reference thereto, and the invention will be finally pointed out in the claim.

In the drawings—

Fig. 1 is a front elevation of a paste tube, showing the cap according to the illustrated exemplary embodiment of the invention attached thereto.

Fig. 2 is a vertical sectional view, taken along the line 2—2 of Fig. 1, showing the valve of the

2

cap in closed position, the tube being shown with its contents removed.

Fig. 3 is a similar view, showing the valve in open position; and showing the tube filled with paste, a strip of the paste being shown extruded.

Fig. 4 is a top plan view.

Fig. 5 is a horizontal sectional view, taken along the line 5—5 of Fig. 1.

Similar reference characters indicate corresponding parts throughout the several figures of the drawings.

Although the invention will find advantageous use with various types of containers, it is particularly advantageous in connection with collapsible tubes of the type for dispensing tooth paste, shaving cream, and the like.

Referring to the drawings, the collapsible tube 10 is of conventional design, being provided at its upper end with an externally threaded neck 11, preferably provided at its upper end with a reduced diameter rim portion 12 having an outlet opening 13. The closure cap, according to the illustrated exemplary embodiment of the invention, comprises a lower cylindrical collar portion 14, internally threaded to engage the threads of the neck 13, an inwardly convergent shoulder portion 15, and a reduced diameter cylindrical top portion 16, closed at its upper end and provided internally with a cylindrical chamber 17 for slidably receiving the valve, as will presently more fully appear. In its end wall the top portion is provided with a central vertically disposed cylindrical passage 18 for receiving the valve stem. In the engaged position of the cap upon the threaded neck of the tube the internal surface of the convergent shoulder portion 15 seats in sealing relation against the upper edge of the rim portion 12, the chamber 16 being of slightly less diameter than the external diameter of the rim portion 12.

An elongated outlet slot 19 is provided in the cap along the junction line between the shoulder portion 15 and the top portion 16, the upper edge of this slot being in the top portion while its lower edge is in the shoulder portion. By means of flat surfaces 20 and 21 the upper and lower edges of the slot are given a substantially sharp knife-like form, these flat surfaces diverging outwardly so that they are not contacted by the extruded strip of paste as the latter is forced from the tube. Preferably, the lower edge of the slot is provided with a series of teeth 22, which impart to the extruded strip of paste a series of longitudinal grooves which are adapted to prevent the paste strip from slipping from a brush or the like.

The valve member 23 is of cylindrical form and is provided with a flat lower surface adapted in its closed position to seat upon the end of the rim portion 12. This flat lower surface forms with the cylindrical peripheral surface a sharp corner 24, which closely engages the inner cylindrical surface of the chamber 16, and constitutes with the knife-like edges of the slot 20, a shearing edge for sharply cutting off the extruded material and preventing any material from lodging in the slot. The valve is provided centrally with a vertical upwardly extending stem 25 slidably engaged in the passage 18, a helical compression spring 26 being engaged about the stem between the upper side of the valve and the top surface of the chamber 16.

In operation, the spring normally maintains the valve closed as shown in Fig. 2. Upon compressing the sides of the tube the paste or other material contained therein is forced out of the opening 13 and lifts the valve against the pressure of the spring, as shown in Fig. 3, the material thereupon being extruded in the form of a flat strip through the slot 19. Upon release of pressure the valve automatically closes under the pressure of the spring, shearing off the extruded strip of material and forcing the material disposed between the upper end of the rim 12 and the under side of the valve back into the tube. It will be observed that the extruded strip is sheared off in line with the knife edges of the slot 19, and that no portion of the extruded strip is in contact with the divergent flat surfaces 20 and 21 extending outwardly from the slot. Hence, there is no possibility of a small amount of material remaining in the slot to become hardened and impair the proper operation of the cap.

I have illustrated and described a preferred and satisfactory embodiment of the invention, but it will be understood that changes may be made therein, within the spirit and scope thereof, as defined in the appended claim.

What is claimed is:

An automatic dispensing cap for collapsible paste tubes and the like having a neck portion 45 provided with an outlet opening in its upper end, comprising a cap member including a lower cylindrical collar portion adapted to be removably engaged with said neck portion, an upwardly

tapered conical shoulder portion having conical inner and outer surfaces, said inner surface adapted to engage with the outer peripheral edge of the upper end of said neck portion, and 5 a cylindrical top portion having a cylindrical chamber therein, and having a cylindrical outer surface forming with said outer conical surface an annular corner, there being a lateral outlet slot partially in said top portion and partially in said shoulder portion having an upper flat wall inclined upwardly and outwardly from the cylindrical surface of said chamber and a lower flat wall inclined downwardly and outwardly from said conical inner surface, said upper and lower walls forming corners at each side of said slot in horizontal line with said annular corner, and a valve member engaged in said cylindrical chamber having a cylindrical peripheral surface and a lower surface forming a relatively sharp shearing edge therewith, and a spring engaged between the upper side of said valve member and the upper end of said chamber normally pressing said lower surface against the upper end of said neck portion with its cylindrical surface sealing said outlet slot.
